VACUUM CLEANER DUST BAG
EMPTYING MEANS

Frank W. Burton, San Diego, Calif.

Application May 23, 1935, Serial No. 23,008

8 Claims. (Cl. 183—52)

My invention relates to a vacuum cleaner dust bag emptying means, and the objects of my invention are:

First, to provide a vacuum cleaner dust bag with an insert portion at its one end which is adapted to be inserted in a paper bag or like bag for emptying the dust bag into the paper bag without losing any of the dust in the transfer;

Second, to provide a means of this class which may be readily secured in the open end of the transfer bag so that the dust cannot escape while transferring from the dust bag to the transfer bag;

Third, to provide a means of this class which may be readily connected to conventional dust bags now in use with but slight changes in the dust bag;

Fourth, to provide a means of this class with a tight cover in connection with the conventional dust bag; and

Fifth, to provide a means of this class which is very simple and economical of construction, easy of operation, efficient in its operation, and which will not readily deteriorate or get out of order.

With these and other objects in view as will appear hereinafter, my invention consists of certain novel features of construction, combination and arrangement of parts and portions, as will be hereinafter described in detail and particularly set forth in the appended claims, reference being had to the accompanying drawing and to the characters of reference thereon which form a part of this application, in which:

Figure 1 is a front elevational view of the fragmentary upper portion of my dust bag positioned in connection with the vacuum handle and showing it in position when the vacuum cleaner is not in operation therefore the bag is partially collapsed; Fig. 2 is a side elevational view of the upper portion of the bag shown in connection with a fragmentary portion of the vacuum cleaner handle and showing the bag in position when the bag is fully expanded and in operating use and showing a portion broken away to facilitate the illustration; Fig. 3 is an enlarged sectional view from the line 3—3 of Fig 2; Fig. 4 is an upside-down view of the cover member shown fragmentarily; Fig. 5 is an enlarged sectional view from the line 5—5 of Fig. 1; Fig. 6 is an enlarged fragmentary sectional view along the line 6—6 of Fig. 1, and Fig. 7 is a diagrammatic view showing a portion broken away and in section showing the positions of the dust bag and the transfer bag in their relation while emptying the contents of the dust bag to the transfer bag.

Similar characters of reference refer to similar parts and portions throughout the several views of the drawing.

The dust bag 1, dust bag insert member 2, cover clips 3 and 4, cover member 5, cover member gasket 6, transfer bag 7, and string 8, constitute the principal parts and portions of my vacuum cleaner dust bag emptying means.

The dust bag 1 is of the conventional type of the various makes. It is however open at its upper end and there is provided an insert member 2 which is adapted to fit into this open upper end. This insert member is an elliptical band provided with a semi-circular groove 2a near its lower side, shown best in Fig. 2 of the drawing, which is adapted to receive a ring 1a which is a conventional form of ring adapted to fit over the upper end of the dust bag 1 and clamp the dust bag into the groove 2a, the ring being separated by means of extended end portions 1b which are clamped by means of a bolt 1c and to this bolt is connected a spring 1d, the opposite end of which is secured to the vacuum cleaner handle H, all as shown best in Fig. 2 of the drawing.

This insert member 2 is provided with an outwardly turned curved flange 2b at its upper side, shown best in Fig. 3 of the drawing. Secured to the side walls at the minor axis sides of said insert member 2 are spring clips 3 and 4 one at each side, the flange 2b being cut away to permit these clip members 3 to extend substantially vertically, as shown best in Fig. 6 of the drawing. Mounted on the upper edge of the insert member 2 is the cover member 5 which is in the form of an elliptical plate, as shown best in Figs. 1 and 4 of the drawing. This cover member 5 is provided with notches 5a at opposite sides of both the major and minor axis of said cover member which are made by cutting away a portion and forming it downwardly so that it extends into the interior of the insert member 2, as shown best in Figs. 5 and 6 of the drawing, thus providing guide means 5b at four points at the major and minor axis thereof. This cover member 5 is provided on its under side, as shown best in Fig. 4 of the drawing, with a gasket 6 which is adapted to form a tight joint between the cover member 5 and the upper curved edge of the insert member 2, shown best in Figs. 3 and 4 of the drawing.

The operation and method of using the means is as follows: When it is desired to empty the dust bag the cover clips 3 and 4 are sprung backwardly a sufficient distance to permit the cover member 5 to be raised, the loops on the ends of the members 3 and 4 passing the inner sides of the notches 5b.

5a with the upward movement of the cover member. When the cover member is removed the transfer bag 7 is positioned down over the insert member 2 so that the lower edge of the transfer bag comes nearly down to the upper edge of the dust bag. Then a string or rubber band 8 is fitted tightly around the outside of the transfer bag 7. Then the dust bag and transfer bag in this position are turned upside down and the contents of the dust bag is emptied into the transfer bag 7, the dust bag being thoroughly shook or pounded so that the contents is transferred from the dust bag to the transfer bag 7; after which the string or resilient band 8 is removed and the insert member is removed from the transfer bag 7 and the cover member 5 placed in position on the insert 2 by springing the members 3 and 4 outwardly. It will be here noted that the flange 2b provides a support to prevent the transfer bag 7 from being easily removed or drawn from over the insert member 2 when it is supported by the member 8. The transfer bag 7 is then tied at its upper end or folded over and disposed of as desired.

25 Though I have shown and described a particular construction, combination and arrangement of parts and portions, I do not wish to be limited to this particular construction, combination and arrangement, but desire to include in the scope 30 of my invention the construction, combination and arrangement substantially as set forth in the appended claims.

35 Having thus described my invention, what I claim as new and desire to secure by Letters Patent is:

40 1. In a vacuum cleaner dust bag emptying means, the combination with an open ended dust bag of an insert member clamped on the inside of the upper end of said dust bag, and a readily removable cover for said insert member, said insert member provided with an outwardly curved flange at its normally upper side adapted to facilitate the securing of a transfer bag on said insert member.

45 2. In a vacuum cleaner dust bag emptying means, the combination with a conventional open ended vacuum cleaner dust bag of an insert member provided with a groove near its lower side, said insert member being a band adapted to fit into the open end of the conventional dust bag, means for securing said dust bag in said groove in said insert member.

50 3. In a vacuum cleaner dust bag emptying means, the combination with a conventional open ended vacuum cleaner dust bag of an insert member provided with a groove near its lower side, said insert member being a band adapted to fit into the open end of the conventional dust bag, means for securing said dust bag in said groove in said insert member, the upper edge of said insert member being turned outwardly in flanged form.

55 4. In a vacuum cleaner dust bag emptying means, the combination with a conventional open ended vacuum cleaner dust bag of an insert member provided with a groove near its lower side, said insert member being a band adapted to fit

into the open end of the conventional dust bag, means for securing said dust bag in said groove in said insert member, the upper edge of said insert member being turned outwardly in flanged form, and a cover member provided with downwardly extended guide members adapted to fit into the upper edge of said insert member.

5 5. In a vacuum cleaner dust bag emptying means, the combination with a conventional open ended vacuum cleaner dust bag of an insert member 10 provided with a groove near its lower side, said insert member being an elliptical band adapted to fit into the open end of the conventional dust bag, means for securing said dust bag in said groove in said insert member, the upper edge of said insert member being turned outwardly in flanged form, a cover member provided with downwardly extended guide members 15 adapted to fit into the upper edge of said insert member, and a gasket interposed between said 20 cover member and the upper edge of said insert member.

25 6. In a vacuum cleaner dust bag emptying means, the combination with a conventional open ended vacuum cleaner dust bag of an insert member 30 provided with a groove near its lower side, said insert member being an elliptical band adapted to fit into the open end of the conventional dust bag, means for securing said dust bag in said groove in said insert member, the upper edge of said insert member being turned outwardly in flanged form, a cover member provided with downwardly extended guide members 35 adapted to fit into the upper edge of said insert member, a gasket interposed between said cover member and the upper edge of said insert member, and spring clip members secured to said insert member and adapted to engage said cover member for holding said cover member in secured relation with said insert member but readily removable therefrom.

40 7. In a vacuum cleaner dust bag emptying means, the combination with a conventional open ended vacuum cleaner dust bag of an insert member 45 provided with a groove near its lower side, said insert member being a band adapted to fit into the open end of the conventional dust bag, means for securing said dust bag in said groove in said insert member, the upper edge of said insert member being turned outwardly in flanged form and a transfer bag adapted to fit over the flanged edge of said insert member.

50 8. In a vacuum cleaner dust bag emptying means, the combination with a conventional open ended vacuum cleaner dust bag of an insert member 55 provided with a groove near its lower side, said insert member being a band adapted to fit into the open end of the conventional dust bag, means for securing said dust bag in said groove in said insert member, the upper edge of said insert member being turned outwardly in flanged form, a transfer bag adapted to fit over the flanged edge of said insert member, and means for securing said transfer bag securely around the outer surface of said insert member.

FRANK W. BURTON.
